Connecticut

Application February 15, 1954, Serial No. 29,042

Term of patent 14 years

(Cl. D17—12)

To all whom it may concern:

Be it known that I, Paul F. Simpson, a citizen of the United States of America, residing in Washington, county of Litchfield, and State of Connecticut, have invented a new, original, and ornamental Design for Clothes Hook, of which the following is a specification, reference being had to the accompanying drawing, forming a part thereof.

In the drawing illustrating my new design:

Fig. 1 is a side elevational view of a clothes hook, showing my new design;

Fig. 2 is a front elevational view of the hook shown in Fig. 1;

Fig. 3 is a top view of the hook, and

Fig. 4 is a bottom view of the hook.

I claim:

The ornamental design for a clothes hook, substantially as shown.
